United States Patent

Des. 238,930

Patented Feb. 24, 1976

238,930

BOTTLE

Royal F. Dadmun, Jr., Baltimore, Md., and James B. Earle, Richardson, and Henry B. Jameson, Jr., Richard V. Kuska, and Daniel A. Leo, Dallas, Tex., assignors to Anderson, Clayton & Co., Houston, Tex.

Filed Oct. 10, 1974, Ser. No. 513,592

Term of patent 14 years

Int. Cl. D9—01

U.S. Cl. D9—160

FIG. 1 is a front elevational view of a bottle, showing our new design;

FIG. 2 is a top plan view thereof; and

FIG. 3 is a bottom plan view thereof.

We claim:

The ornamental design for a bottle, substantially as shown.
